Primary Examiner — Marie D. Fast Horse(74) *Attorney, Agent, or Firm* — Sheppard Mullin Richter & Hampton LLP(57) **CLAIM**

The ornamental design for a portable payment machine, as shown and described.

DESCRIPTION

FIG. 1 is a front view showing a portable payment machine showing my new design;

FIG. 2 is a rear view thereof;

FIG. 3 is a left-side view thereof;

FIG. 4 is a right-side view thereof;

FIG. 5 is a top view thereof;

FIG. 6 is a bottom view thereof;

FIG. 7 is a front perspective view thereof; and,

FIG. 8 is a rear perspective view thereof.

1 Claim, 4 Drawing Sheets
